UNITED STATES PATENT OFFICE.

RICHARD D. KELLY, OF THE DALLES, OREGON.

WATER-WHEEL.

1,017,002.

Specification of Letters Patent. Patented Feb. 13, 1912.

Application filed April 19, 1911. Serial No. 621,990.

To all whom it may concern:

Be it known that I, RICHARD D. KELLY, a citizen of the United States, residing at The Dalles, in the county of Wasco and 5 State of Oregon, have invented certain new and useful Improvements in Water-Wheels, of which the following is a specification.

This invention relates to improvements in water wheels and has for its object to provide a wheel which may be installed in the bed of a stream and which may be operated by the current thereof.

A further object is to provide such a wheel which will receive the force of the current 15 simultaneously against its opposite sides, operating in the same direction about its axis, thereby distributing the strain upon the wheel by balancing the force applied upon one side against that applied upon the other, 20 and at the same time relieving the base structure from such strain.

I accomplish these objects by the mechanism illustrated in the accompanying drawing in which—

25 Figure 1 is a vertical sectional view of my improved wheel. Fig. 2 is a longitudinal section on the line $\alpha-\alpha$ of Fig. 1.

Similar characters of reference indicate 30 similar parts in each of the views.

35 In the drawing 1 represents a shaft mounted in a concrete base or other suitable structure, and provided with a bevel gear 13 meshing with a similar gear 14, on the transmission rod 15.

Upon the shaft 1 is placed the sleeve or 40 extended hub 12, provided with terminal flanges 16, to which are secured the radiating arms 10, by means of bolts 17. The flanges each carry the same number of arms 45 and a rim 11 is formed at the outer ends thereof, at each end of the wheel, holding them at equal distances apart, so that one arm at each end will be opposed by one at the other. To each rim, between the end-

50 arms, at 2 is pivotally secured a bracket 18, and thereto is fixed the blades 2, 3, 4 etc. These blades are all free to swing between their respective arms and are of a width which permits the free edges to clear the outer arms as the blades swing against the 55 rim. When the blade swings back to its initial position, against the other arm, the bracket, which is bent at an angle, is so positioned that the outer edge of the blade comes against the rim 11, while the side thereof will lie against the arms.

To each pair of arms, as referred to the opposing rims 11, are secured, in a similar manner, brackets 19, upon the pivots 9. Upon these brackets are fixed blades a , b , c etc. the outer edges of which are made to fit neatly against the free edges of their corresponding exterior blades, when all are in their initial position.

In Fig. 1 the descending side of the wheel 65 shows the blades in what may be termed their initial position, and the horizontal arrows indicate the direction of the current. It will be seen that force will be exerted against the blades immediately after they 70 pass the horizontal position, which will continue until they approach that position at the opposite side.

When the wheel shall have turned sufficiently for the water to engage the free edge 75 of the inner blade, that blade will immediately swing downward and outward, carrying with it the outer blade, to the position clearly illustrated in Fig. 1. Here the exterior wing stands with its side to the rim, 80 while the inner blade is inclined downwardly and outwardly against the side of the outer blade, so as to obstruct the current and cause an upward force at that side of the wheel. The force of the current is, therefore, directed against the lower side of the 85 blades in the ascending portion of the wheel, while it is applied against the opposite side thereof, in the descending portion. This will be true in cases where the water approaches the median point of the wheel, and 90 will continue until those blades reach a horizontal position, at the upper portion.

It is apparent that the force applied 95 against the blades in the ascending portion of the wheel will counterbalance a large part of that exerted against the descending portion, thereby greatly reducing the strain upon the wheel and the supporting base, and greatly increasing the power transmitted 100 through the shaft 15.

This wheel is adapted to use in shallow water, but will work equally well in deep water and may be completely submerged.

Having described my invention, what I 105 claim is—

1. A water wheel comprising an extended hub having a series of arms radiating from each end, the arms of the one end being paired against those of the other, a rim secured upon the ends of each series of arms whereby the latter are maintained at equal 110

distances apart, a blade adapted to lie upon each pair of arms, and blade holders having a shank bent at an angle and pivotally secured to the rim at a point intermediate 5 of said arms, whereby the outer edges of said blades will lie against the rim in the descending portion of the wheel and the free edges will swing outwardly against the rim at the adjacent arm, in the ascending 10 portion.

2. The combination in a water wheel comprising an extended hub having a series of arms radiating from each end, the arms of one end being paired against those of the 15 other, a rim secured upon the ends of each series of arms whereby the latter are maintained at equal distances apart, a blade adapted to lie upon each pair of arms, blade holders each having a shank bent at an 20 angle and pivotally secured to the rim at a

point intermediate of said arms whereby the outer edge of said blades will lie against the rim in the descending portion of the wheel and the free edges will swing outwardly against the rims at the adjacent 25 arms, in the ascending portion, and a blade pivotally secured to each pair of arms and bearing thereupon in the descending portion of the wheel with its outer edge resting against the free edge of the outer blade and adapted to swing outwardly so that the free edge will bear at an angle against the side of the outer blade in the ascending portion 30 of the wheel.

In testimony whereof I affix my signature 35 in presence of two witnesses.

RICHARD D. KELLY.
